UNITED STATES PATENT OFFICE

WILBER L. LONG, OF KIRKSVILLE, MISSOURI

INCUBATOR

Application filed October 8, 1929. Serial No. 398,242.

This invention relates to incubators, and has for one of its objects to provide a novel, simple and highly efficient apparatus of this character which shall be adapted to employ as a warming medium air heated outside thereof and forced thereinto and which shall be adapted to utilize as a warming medium air heated by the apparatus forming the subject matter of Patent #1,694,351, granted to me December 4, 1928.

The invention has for a further object to provide an incubator of the character stated which shall embody a cabinet and a hot air conduit located within the cabinet and adapted to receive the air from the heating apparatus and distribute it throughout the cabinet in the most effective manner.

The invention has for a further object to provide an incubator of the character stated wherein the hot air conduit shall be located close to the bottom of the cabinet and wherein in the cabinet shall have inner rounded corners to effect the uniform distribution and the free movement of the hot air throughout the cabinet.

The invention has for a further object to provide an incubator of the character stated wherein the hot air conduit shall be located parallel to the bottom wall of the cabinet and supported in a manner to permit it to be adjusted toward and away from said wall.

The invention has for a further object to provide an incubator of the character stated wherein the cabinet shall be provided in the top thereof with air outlet ports of such formation as to permit the free passage of air therethrough and which shall embody novel and readily adjustable means for varying the effective size of the ports.

The invention has for a further object to provide an incubator of the character stated which shall embody egg tray supporting means of such construction as to permit the trays to be readily mounted thereon or removed therefrom and adjusted vertically with respect to the cabinet.

The invention has for a further object to provide an incubator of the character stated with means through the medium of which the trays may be readily adjusted on their sup-

porting means to and secured in a horizontal or a forwardly or rearwardly inclined position without opening the cabinet.

The invention has for a still further object to provide an incubator of the character stated which shall embody a hatching compartment adapted to be warmed by hot air conveyed thereto by the hot air conduit of the cabinet and embodying a construction adapted to permit the shedding down of the chicks to be conveyed therefrom by the passage therethrough of the heated air.

With the foregoing and other objects in view, the nature of which will appear as the description proceeds, the invention consists in the construction, combination and arrangement of parts hereinafter fully described and claimed, and illustrated in the accompanying drawings, wherein:

Figure 1 is a view partly in side elevation and partly in vertical section of an incubator constructed in accordance with my invention;

Figure 2 is a sectional view taken on a plane extending horizontally through the incubator at a point adjacent the upper side or wall or floor thereof;

Figure 3 is a sectional view taken on the vertical plane indicated by the line 3—3 of Figure 2;

Figure 4 is a sectional view taken on the vertical plane indicated by the line 4—4 of Figure 1;

Figure 5 is a view partly in side elevation and partly in vertical section of the air heating apparatus;

Figure 6 is a sectional view taken on the horizontal planes indicated by the line 6—6 of Figure 4;

Figure 7 is a detailed view illustrating the manner in which the trays of each series are connected together for adjustment simultaneously into a horizontal or inclined position;

Figure 8 is a perspective view of one of the brackets by which the trays are connected to the slides;

Figure 9 is a perspective view of a fragmentary portion of one of the slides;

Figure 10 is a sectional view illustrating the means for controlling the escape of heated air from the cabinet of the incubator;

Figure 11 is a sectional view taken on the horizontal plane indicated by the line 11—11 of Figure 1;

Figure 12 is a sectional view taken on the 5 plane indicated by the line 12—12 of Figure 5;

Figure 13 is a sectional view through the hot air conduit illustrating a modified form of the air outlet ports therefor, and

10 Figure 14 is a similar view illustrating a further modified form of the air outlet ports.

Referring in detail to the drawings, 1 designates the cabinet of the incubator which is of elongated rectangular formation in plan 15 and comprises a bottom wall 2, side walls 3, a top wall 4, a front wall 5 and a rear wall 5^a. The walls 3 consist of doors 6, 7 and 8. The doors 6 and 7 are secured by hinges 9 to posts 10, and the door 8 is secured by hinges 11 to 20 the rear wall 5^a. The walls 2-5^a may be of any construction adapted to prevent the radiation of heat therethrough. Strips 12 are secured in all of the inner corners of the cabinet 1, and are provided with concave inner faces to insure the unobstructed circulation of the heated air within the cabinet.

The air for warming the cabinet 1 is heated in an apparatus 13 which is located outside of the cabinet, and comprises a chamber 14 30 closed at one end and communicating at its other end with the intake port 15 of a blast fan or blower 16, an electric heating unit 17 located within the chamber 14, and annular chambers 18 surrounding the chamber 14 and 35 provided with ports 19 which establish communication between the chambers 18 and between said chambers and the chamber 14, certain of the ports communicating with the atmosphere. The air flows through the chambers 18 into the chamber 14 and during its 40 circuitous passage through the chambers 18, it is initially heated. During its passage through the chamber 14, the air is heated to a higher degree and it is forced from this 45 chamber into a conduit or pipe 20 by the blast fan 16. The conduit 20 is located within the cabinet 1 and is connected to the discharge port 21 of the blast fan 16. The impeller of the blast fan 16 is operated by an electric 50 motor 22, and the blades 23 of the impeller are secured in slots 24 formed in the armature shaft 25 of the motor. Each pair of the blades 23 is formed from a single blank, and the slots 24 extend longitudinally of the armature shaft 25 and intersect each other at the axis of the shaft. The connected edge portions of the blades 23 are located in the slots 24, and they are secured to the armature shaft 25 by a nut 26 which is engaged with the outer end of the shaft and contacts with the outer edges of the blades. As the air heating apparatus 13 forms the subject matter of the patent hereinbefore identified, it is believed that a further description of the 60 apparatus is unnecessary.

The conduit 20 extends through the front and rear walls 5 and 5^a of the cabinet 1, and it is located centrally within the lower portion of the cabinet. The conduit 20 is closed at its rear end and the open front end thereof extends through a vertical slot 27 formed in the front wall 5. A slide 28 greater in length and width than the slot 27, constitutes a vertically adjustable closure for the slot, and contacts with the outer surface of the front wall 5. 70 The slide 28 is held against the outer surface of the front wall 5 by a guide 29 which is secured, as at 30, to said wall. The front end portion of the conduit 20 passes through and has a snug fit in an opening 31 in the slide 28. The slide 28 supports the front end of the conduit 20 for adjustment toward and away from the bottom wall 2 of the cabinet 1, and the front end of the conduit is secured in adjusted position by elements 32 passing through the 80 slide 28 and engaging the front wall 5. The rear end of the conduit 20 is also supported for adjustment toward and away from the bottom 2 of the cabinet 1 by means similar to that employed for adjustably supporting the 85 front end of the conduit. The slot, slide, guide and the slide securing elements of said rear means are designated 27^a, 28^a, 29^a and 32^a, respectively. To permit the adjustment of the conduit 20, the front or intake end thereof is connected by a flexible coupling 33 to the discharge port 21 of the blast fan 16.

The conduit 20 is provided in its lower side and at opposite sides of its vertical center with outlet ports 34 which may be circular, 100 as shown in Figures 1 and 13, and the conduit may be provided with lips 35 extending downwardly from the upper walls of the ports as shown in Figure 13. If desired, the outlets of the conduit 20 may be in the form of arcuate slots 36, as shown in Figure 14. The heated air, as it is delivered to the conduit 20 by the blower 16, flows under high velocity from the outlet port 34 of the conduit, the velocity of the air being greater than it is possible to impart to air by convection alone. The heated air flows downwardly from the conduit 20 into the cabinet 1 at opposite sides of the longitudinal center of the cabinet, and after impinging against the bottom wall 2, is 110 deflected upwardly by the lower corner strips 12. The heated air flows upwardly against the sides 3, and when it reaches the upper corner strips 12, it is deflected by said strips along the top wall 4. The air passes from the cabinet 1 through series of outlet ports 37 which are formed in the top wall 4 and have upwardly tapering convex walls to permit the free passage of air therethrough. The outlet ports 37 are under the control of dampers 38 which are provided with openings 39 and are slidably mounted in guides 40 secured to the upper surface of the top wall 4. The dampers 38 may be adjusted in the guides 40 to entirely close the outlet ports 37 or to fully or 120

partly uncover the ports, and any suitable means, such as knobs 41, may be secured to the dampers 38 to permit the ready adjustment of the latter. The streams of air issuing from the ports 35 or 36 of the conduit 20 spread out as they strike the bottom wall 2, and then circulate around the cabinet as hereinbefore pointed out. When the ports 34 or 36 are provided at their upper walls with the lips 35, the streams of air issue from the ports in planes at right angle to the axis of the conduit 20. The streams of air issuing from the conduit 20 impinge, against the floor 2 of the cabinet 1, and the force under which they are directed against the floor controls to a considerable extent the rapidity of the ascent of the air in the cabinet. The force under which the air streams impinge against the floor 2 of the cabinet 1 may be varied to regulate and control the ascent of the air in the cabinet, and this may be accomplished by adjusting the conduit 20 upwardly or downwardly with respect to the floor. By adjusting the conduit 20 downwardly, the force under which the air streams impinge against the floor 2 of the cabinet 1 is increased and by adjusting the conduit upwardly, the force under which the air streams impinge against the floor is decreased.

Tracks or guides 42 of elliptical formation in contour are arranged within the cabinet 1 with their major axes disposed vertically. The tracks or guides 42 are provided at their lower ends with downwardly extending arms 43 which are arranged in socket members 44 secured to the bottom wall 2 of the cabinet 1, and they are provided at their upper ends with upwardly extending arms 45 which are arranged in socket members 46 secured to the top wall 4 of the cabinet. The arms 43 and 45 are located at the front sides of the tracks or guides 42. The arms 43 and 45 and the sockets of the members 44 and 46 are of rectangular formation in horizontal section, and the arms have a snug fit in the sockets to hold the tracks or guides 42 in vertical position within the cabinet 1. The tracks or guides 42 have their upper ends spaced from the top wall 4. The distance between the upper ends of the tracks or guides 42 and the top wall 4, and the relative lengths of the arms 43 and 45, are such as to enable the arms to be readily applied to and removed from the socket members 44 and 46 without detaching such members from the walls 2 and 4. The tracks or guides 42 are arranged in pairs with the adjacent tracks or guides in contact and with their arms 43 and 45 secured together by bolts 42^a, the connected arms of the adjacent tracks or guides being arranged in a pair of the socket members 44 and 46.

The tracks or guides 42 are provided with elliptical grooves 47 and elliptical slots 47^b, the slots being located in the inner or oppos-

ing sides of each pair of the tracks or guides and communicating with the grooves.

Slides 48 of elongated rectangular formation and having rounded ends 49 are located within the grooves 47 of the tracks or guides 42 with their rounded ends in contact, and they are adapted to be inserted in tracks or guides by way of openings 50 formed in the lower end portions of the front sides of the tracks or guides. A lug 51 is carried by each of the slides 48 near one end of the latter, and the lugs project through the slots 47^b to points beyond the inner sides of the tracks or guides 42. Egg carrying trays 52 of elongated rectangular formation in plan and provided with perforated bottoms 53 are arranged between each pair of the tracks or guides 42 and are detachably connected to the slides 48 through the medium of brackets 54 of inverted U-form. The brackets 54 are secured to the sides of the trays 52 centrally between the ends of the latter and embrace the lugs 51. A number of trays 52 are supported one above the other by the front vertical slides 48 of each pair of the tracks or guides 42. The lowermost of the vertical front slides supports the slides and trays disposed thereabove, as shown in Figure 4. In order to remove the trays 52 from the supporting lugs 51, the trays are lifted off therefrom by vertical movement without movement of the slides 48. The trays can be moved in unison in order to lower the trays by moving the lowermost vertical slide 48 rearwardly and permitting the succeeding slide 48 to engage the horizontal run of the track or guide 42.

The widths of the grooves 47 and of the slots 47^b are greater than that of the slides 48 and the lugs 51 respectively, to permit the slides to move freely in the guides 42, and the width of the grooves at the lower rear corners of the guides is sufficient to permit the lowermost of the slides of the rear vertical series to move into the lower horizontal portions of the grooves while trays are being drawn forwardly with relation to the guides preparatory to removing the trays from their slides.

The series of trays 52 arranged between each pair of the tracks or guides 42 are held together by straps 55 which are pivotally and removably connected to the sides of the trays, as at 56.

As they are connected together by the straps 55 and as the brackets 54 thereof are rockably connected to the slide lugs 51, the trays 52 of each series may be moved into and maintained in a horizontal position or a downwardly and forwardly inclined position or a downwardly and rearwardly inclined position, the rocking of the trays from one position to another effecting the turning of the eggs. The means for rocking the trays comprises a shaft 57 journaled in bearings 58

carried by the tracks or guides 42 and bearings 59 carried by the front and rear walls 5 and 5^a of the cabinet 1, and arms 60 fixed at their centers to the shaft and resting upon the sides of the uppermost trays. The shaft 57 extends beyond the front wall 5 and is provided with a crank 61 through the medium of which it may be turned to rock the trays 52, and a pawl 62 pivoted to the front wall 5 and engaging a ratchet wheel 63 on the shaft serves to hold the shaft and the trays in adjusted position.

10 The cabinet is separated into compartments by transverse partitions 64 and two 15 or more series of the trays 52 and their supporting means may be arranged in each of the compartments. The partitions 64 comprise lower sections 64^a and upper sections 64^b which are connected together by hinges 20 64^c. The partitions 64 are provided with vertical slots 65 for the passage and adjustment of the conduit 20.

25 The trays 52 and their supporting means are arranged within the cabinet 1 at opposite sides of the conduit 20, and the trays on one or both sides may be used. When it is desired to use the trays 52 on one side only, partitions 66 are arranged within each of the cabinet compartments between the trays that 30 are not to be used and the conduit 20.

35 These partitions comprise lower sections 66^a and upper sections 66^b, respectively, which are hinged together, as at 66^c to permit them to be easily erected within the compartments.

40 The partitions 66 contact with the bottom, side and top walls of the compartments, and when they are used, those outlet ports of the conduit 20 near the partitions are closed by plugs or in any other suitable manner.

45 The incubator embodies a hatching compartment 67 which is arranged at the rear end thereof and into which the conduit 20 extends to provide it with heated air. Strips 68 similar to the strips 12 are secured in the inner corners of the hatching compartment 67 and their concave outer faces insures an unobstructed path for the heated air through this compartment. The top wall 69 of the hatching compartment 67 inclines upwardly 50 in the direction of the vertical longitudinal center of the compartment, and is provided in its upper edge with an air discharge slot 70. The walls 70^a of the slot are curved and converge upwardly to insure the free passage 55 of the air therethrough. The air is delivered to the bottom of the hatching compartment 67, and during its upward passage through the compartment carries out any down shed by the chicks.

60 While I have described the principle of the invention, together with the structure which I now consider the preferred embodiment thereof, it is to be understood that the structure shown is merely illustrative and 65 that such changes may be made, when de-

sired, as fall within the scope of the invention as claimed.

I claim:—

1. An incubator comprising a cabinet provided in opposite walls thereof with vertical 70 slots, egg carrying trays within the cabinet, a conduit arranged horizontally within the cabinet and extending through said slots, the conduit having one end closed and provided in its lower side with discharge ports, slides 75 closing the slots and having the ends of the conduit passing therethrough, means supporting the slides for vertical adjustment, means for securing the slides in adjusted position, and means for delivering heated air 80 to the other end of the conduit.

2. An incubator comprising a cabinet, means for supplying heat to the cabinet, a pair of relatively spaced guides vertically within the cabinet, slides within the guides 85 and provided with lugs, a vertical series of egg carrying trays rockably connected to the lugs of certain of the slides, straps pivotally connected to the trays, a shaft passing horizontally through the cabinet, arms secured to the shaft and contacting with the highest tray, a crank secured to the outer end of the shaft, and means for holding the shaft against accidental turning movement.

3. An incubator comprising a cabinet, 95 means for heating the cabinet, elliptical guides arranged within the cabinet with their major axes vertically disposed, the guides being relatively spaced and provided with elliptical grooves and slots, the slots being 100 located in the opposing faces of the guides and communicating with the grooves, the guides being provided in their lower front sides with openings and the front portions of the lower walls of the grooves of the guides being horizontal and communicating with said openings, slides within the grooves of the guides and provided with lugs extending through the slots of the guides, the slides being insertable into the grooves through said 105 openings and the lowermost front slides being supported in vertical position by said horizontal wall, egg carrying trays between the guides, and means securing the trays to the lugs of certain of the slides.

4. An incubator comprising a cabinet having an imperforate bottom wall and provided in its top wall at opposite sides of its longitudinal center with discharge ports, means for varying the effective area of the discharge 110 ports, egg carrying trays arranged within the cabinet above the bottom wall thereof, a conduit arranged in the longitudinal center of the cabinet between the bottom wall thereof and the egg carrying trays and provided with discharge ports, means for delivering heated air to the conduit, the discharge ports of the conduit being located therein to direct the heated air against the bottom wall of the cabinet, means supporting the conduit for 115 120 125 130

adjustment toward and away from the bottom wall of the cabinet to vary the force under which the heated air is delivered against said wall, the means for delivering heated air to the conduit being located outside of the cabinet, and means establishing a flexible connection between the conduit and the air heating and delivering means to permit the conduit to be adjusted with respect to said means.

5. An incubator comprising a cabinet provided above its bottom wall with a discharge port, egg receiving trays in the cabinet, a pipe located in the cabinet in close parallel relation to the bottom wall and provided at its lower side with discharge ports, and means for heating air and delivering the heated air under high velocity from the pipe.

6. An incubator comprising a cabinet provided above its bottom wall with a discharge port, egg receiving trays in the cabinet, means for heating air and delivering the heated air to the cabinet, and means for supporting said first named means for adjustment toward and away from the bottom wall to vary the force under which the air issuing from the discharge ports of the pipe impinges against said wall and thus control the rate of ascent of the air in the cabinet.

30 In testimony whereof I hereunto affix my signature.
